UNITED STATES PATENT OFFICE

SEVERIN HALVORSEN, OF CHICAGO, ILLINOIS, ASSIGNOR TO THE NEWSPAPER STUFFING MACHINE COMPANY, OF SEATTLE, WASHINGTON, A CORPORATION OF WASHINGTON

DELIVERY MECHANISM FOR NEWSPAPER STUFFING MACHINES

Application filed October 25, 1926, Serial No. 143,851. Renewed September 26, 1929.

My invention relates to delivery mechanisms for newspaper stuffing or similar machines, particularly mechanisms in which newspapers or other articles are fed to the bottom of a pile so that they may be removed manually or otherwise from the top of the pile.

One of the objects of my invention is to provide a simple, practical and efficient delivery mechanism of the class specified.

Another object of the invention is to secure quickness and accuracy of operation.

A further object of the invention is to assure proper piling of the papers or articles and to prevent the papers from falling over or opening while being piled.

These and other objects and advantages will appear and be brought out in the following specification and drawings, in which

Fig. 1 is a side view of a machine embodying my invention;

Fig. 2 is an end view of the same;

Fig. 3 is a cross sectional view of the same along line 3—3 of Fig. 1, and

Figs. 4 and 5 are details of construction.

My present invention finds its greatest applicability in newspaper delivery machines such as shown in my copending application Serial No. 562,463, filed May 20, 1922, for delivery mechanisms.

Referring to the drawings, I show a delivery mechanism for piling and delivering newspapers, so that the newspapers may be introduced or inserted into the bottom of the pile and continually pushed upward so that they may be taken off at the top. I show a body frame having an upright 1 which may be suitably mounted on the floor or otherwise; also a hopper member 2 in front of body member 1. Member 2 has a hopper 3 into which the articles to be piled and delivered are fed. In the stuffing machine the completed newspapers are preferably fed to the delivery mechanism in an upright position as being most advantageous for the stuffing operation.

Fig. 2 shows a newspaper A just ejected from the stuffing machine and ready to be delivered by the delivery machine. The movement of the finished newspaper A is

accomplished by the newspaper stuffing machine which is understood to be associated with and located immediately adjoining the delivery mechanism set forth herein. A roller 5 is shown for feeding the newspapers to the hopper, such roller being part of the stuffing machine and being mounted on a shaft 6 supported in bearings 7—7 and driven by gear wheels 8, 9 and 10 suitably supplied with power.

The newspaper A coming into hopper 3 is engaged and swung upwardly so that it assumes a horizontal position at the top of chamber 3 as shown in Figs. 2 and 3 in which position it is supported by abutments 12 and 13. The newspapers are thus fed one after the other into the chamber 3 and then engaged and swung upwardly so as to form a pile, the papers being fed to the bottom of the pile and the whole pile being elevated little by little and the upper end of the same being free so that the papers may be taken from the pile by hand or otherwise in any desired number.

The engaging and swinging mechanism involves a swinging plate 15 having one end provided with a plurality of hooks 16, the plate 15 being adapted to act against the side of the newspaper and arranged to swing so as to move and lift the paper from a vertical position to a horizontal position. The hooks 16 engage the lower or folded edge of the paper and hold it in proper position during the upward swinging movement, the member 2 having a curved surface 18 corresponding substantially with the curve made by the folded edge of the newspaper as it is swung upwardly.

The actuating plate 15 with its hooked member 16 is operated by a suitable mechanism to give it the requisite swinging movement. This mechanism comprises a swinging arm 19 pivotally connected at 20 to the back of plate 15. The arm 19 is pivotally mounted on shaft 21 which latter is supported in frame 1. Said arm 19 is actuated by a reciprocating link 22 pivoted to the arm at 23. Link 22 is connected at 25 to a rotary wheel 26 so that the rotation of wheel 26 will actuate link 22 to swing arm 19 backwardly and forwardly to lift paper A into horizontal position and

then to retract and come into position to engage another paper in vertical position and swing the same into horizontal position. Wheel 26 is mounted on a shaft 27 having bearings 28.

In order to insure that the paper will lie flat against plate 15 and not fall forward or open, means are provided to direct a flow of air to the paper at the proper interval. To this end, member 2 is provided with apertures 101 through which project the ends of pipes 102 which latter are connected through a rotary valve 103 to a suitable source of air pressure at 104. Valve 103 is mounted on member 2 and is operable by shaft 105 which has secured to it a rocker arm 106. Arm 106 is pivotally connected at 107 with link 108 which is also pivotally connected at 109 to rocker arm 59 which latter is reciprocated by link 57 and gear 61 as described in the above referred to copending application. The oscillation of shaft 105 by this mechanism opens and closes valve 103 to direct a flow of air against the front of the paper just after the latter has been received into the delivery machine and while it is being lifted from the vertical to the horizontal position. This action serves to keep the paper from falling forward or crumpling and minimizes the likelihood of bending or tearing of the sheets.

As a means of holding the papers in the stack or pile previous to removal therefrom I show abutments 12 and 13. Abutments 12 are formed out of members 30 which are pivoted at 31 and have link connections at 110 and 111 with arms 112 which latter are mounted on shaft 105 adjacent to arm 106 which is provided with dog 115 cooperable with ratchet 114. Cam wheel 116 is secured to ratchet 114 so as to be rotatable with it and has cams 117 which actuate shaft 113 through arm 118 and pin roller 119. A spring 120 fastened to arm 121 of shaft 113 tends to keep member 30 in the position shown in Figs. 2 and 3. The timing of the cam and ratchet wheels is such that members 30 are withdrawn from the position shown just as the plate 15 with the paper upon it is passing and are returned to position before the return of the plate. Fingers 16 protrude beyond the edge of plate 15 and operate in apertures in member 2.

It will be understood that changes and modifications may be made without departing from the spirit of the invention.

What I claim is:

1. A machine of the class specified having a member for engaging an article in a substantially vertical position and swinging it up to substantially horizontal position and means for directing a blast of air toward the member to hold said article in place thereon prior to and during said action.

2. A machine of the class specified having a swinging plate device for engaging a flat

side of a paper or similar article and swinging the same from a substantially vertical position to the horizontal and placing it at the bottom of a pile or stack of similar articles, and means for directing a blast of air toward the unengaged side of said article for keeping it in engagement with said device during said swinging operation.

3. A machine of the class specified having a hopper into which articles may be fed in substantially vertical position, a swinging platen adapted to engage said articles and swing them from such vertical to horizontal position and place them at the bottom of a stack or pile of similar articles arranged one upon another, and means for directing a blast of air toward the member to hold said articles against said platen and prevent the same from falling over or crumpling.

4. A machine of the class specified having a moving member for engaging an article and placing it at the bottom of a stack or pile of similar articles arranged one upon another, and means for directing a blast of air toward the member to hold said article in position for said engagement.

5. A machine of the class specified having means for lifting and turning a substantially flat article from the vertical to the horizontal and placing it at the bottom of a stack of similar articles and means cooperable therewith for effecting said engagement, said means being adapted to direct a discontinuous blast of air toward said first mentioned means.

6. In a machine of the class specified the combination of means for turning, lifting and stacking articles, means for directing a blast of air toward the article to prevent it from falling and crumpling, and means for holding said stack substantially as described.

7. A machine of the class specified having means for acting upon an article in a substantially vertical position and swinging it up to a substantially horizontal position, and a pipe and valve whereby a blast of air may be directed against said article to hold it in place prior to and during said action.

8. A machine of the class specified having means for engaging an article and placing it at the bottom of a stack or pile of similar articles arranged one upon another, and a device having a valve and pipes for directing a blast of air against said article to hold it in position for said engagement.

9. A machine of the class specified having a swinging plate device for engaging a flat side of a paper or similar article and swinging the same from a substantially vertical to a horizontal position, and placing it at the bottom of a pile or stack of similar articles, and means for directing a blast of air against each article as it passes through said machine to keep it in engagement with said plate device during said swinging operation.

10. A machine of the class specified having a hopper into which articles may be fed in a substantially vertical position, a swinging platen adapted to engage said articles and swing them one by one from such vertical to a horizontal position and place them at the bottom of a stack or pile of similar articles arranged one upon another, and a device for directing a blast of air through said hopper towards said article for holding it against said platen and preventing the same from falling over or crumpling, and means for controlling said blast.

5
10
15
20 11. In a machine of the class specified, the combination of means for engaging and stacking flat articles at the bottom of a stack of similar articles with means for directing a blast of air against an article during said engagement, and mechanism for receiving and holding said articles when so stacked.

20 In witness whereof, I hereunto subscribe my name this 16th day of October, A. D. 1926.

SEVERIN HALVORSEN.
